(57) **CLAIM**

The ornamental design for a display panel or portion thereof with graphical user interface, as shown and described.

DESCRIPTION

This application is related to U.S. utility patent application Ser. No. 15/968,673, filed on May 1, 2018, and entitled “Matching Content to a Spatial 3D Environment.” The contents of the aforementioned patent applications are hereby expressly and fully incorporated by reference in their entirety, as though set forth in full.

The sole FIGURE is a front view of a display panel or portion thereof with a graphical user interface showing our design.

The outermost broken line rectangle illustrates a display panel or portion thereof that forms no part of the claimed design. The remaining broken lines, including all text, illustrate portions of the graphical user interface or mixed reality environment and form no part of the design.

The stippling represents a contrasting appearance and forms part of the claimed design.
